UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

FIRING MECHANISM OF BREECH-LOADING ORDNANCE.

1,116,392.

Specification of Letters Patent. Patented Nov. 10, 1914.

Application filed July 20, 1911. Serial No. 639,488.

To all whom it may concern:

Be it known that we, ARTHUR TREVOR DAWSON, knight, and GEORGE THOMAS BUCKHAM, both subjects of the King of Great Britain, residing at Vickers House, Broadway, Westminster, in the county of London, England, have invented certain new and useful Improvements in or Relating to the Firing Mechanism of Breech-Loading Ordnance, of which the following is a specification.

This invention relates to the firing mechanism of breech-loading guns.

We have already devised a combined electric and percussion lock, the striker of which is under the influence of a cocking and firing lever and is slightly retracted into a safe position during the first movement of the block actuating crank, by a portion of the latter coöperating with the cocking and firing lever, the cocking and release of the striker when firing percussively being effected through the intervention of a transverse shaft having a member so situated in relation to two arms mounted on separate spin-dles that the rotary movement of the transverse shaft in one direction cocks the striker through one of the said arms and movement of the transverse shaft in the reverse direction releases the striker through the other of the said arms.

We now propose to dispense with the necessity for moving the shaft in two directions for cocking and releasing the striker, and to effect the cocking and releasing by one movement of a cocking and firing lever working on the slip-lock principle. For this purpose the said cocking and firing lever may be mounted on the same axis pin with a tripping lever, the former being loose and the latter keyed thereon. The tripping lever has pivoted near its free end a tripping piece furnished with two arms one of which engages with a notch or groove in the cocking and firing lever and the other with a stationary surface on the case inclosing the firing mechanism.

In order that the said invention may be clearly understood and readily carried into effect, we will describe the same more fully with reference to the accompanying drawings, in which:—

Figure 1 is a plan (partly in section) of the breech end of a gun provided with our improved firing mechanism. Fig. 2 is an

enlarged view of a part of Fig. 1 showing more clearly the firing mechanism. Fig. 3 is a horizontal section of the breech of the gun with the mechanism in the fired position. Fig. 4 is a vertical section taken approximately on the line 1—1 of Fig. 3. Fig. 5 is an enlarged view of a part of Fig. 4, and Figs. 6 and 7 are enlarged views showing parts of the firing mechanism in the position they occupy in Fig. 4 and Fig. 3 respectively. 60 65

A is the breech end of the gun, B the breech block, C the breech actuating hand lever, C' the crank for moving the breech block and C² the actuating spindle.

E is the striker of the firing mechanism, e 70 the insulated electric needle, E^x the cocking and firing lever, C'x the cam surface on the crank C' for engaging with the cocking and firing lever E^x to retract the striker, and E' is the rotary transverse shaft for cocking 75 and releasing the striker.

The detachable lock casing F contains the firing lever E^x, the tripping lever E², the tripping piece e' pivoted thereto, the main spring F^x, the striker E and the electric 80 needle e together with the electrical connections therefor. The shaft E' is provided at its outer end with a firing arm E³ and at its inner end with a firing cam or lever e² which is in engagement with an intermediate firing lever e³ carried by a spindle E⁴. The said spindle is formed with a guide member e⁴ in which is disposed a lever e⁵ connected to the axis pin E⁵ to which the tripping lever E² is keyed and on which 90 the cocking and firing lever E^x is loosely mounted.

The parts of the firing mechanism normally occupy the position shown in Figs. 3, 4, 5 and 6. When the firing arm E³ and its 95 shaft E' are operated to fire the gun percussively a corresponding movement is imparted to the firing and tripping lever axis pin E⁵ through the medium of the levers e², e³ and e⁵. This movement of the said axis 100 pin actuates the tripping lever E² which as above stated is keyed thereto. The arm e⁶ Figs. 5, 6 and 7 of the tripping piece e' carried by the said lever E², by its engagement in the notch or groove E⁶ in the cocking and firing lever E^x imparts to the latter the angular movement necessary to cock the striker. During this movement the other arm e⁷ of the tripping piece e' is prevented 105 from moving by the engagement of a lateral 110

projection e^s with the part f (Fig. 7) of the lock case F, with the result that the arm e^s of the tripping piece is gradually displaced from its notch or groove E^s in the cocking and firing lever during the retraction of the latter until it becomes liberated as shown in Figs. 1, 2 and 7. Owing to the fact that it is loosely mounted on the axis pin E^s , the said firing lever flies forward with the 10 striker under the influence of the main spring F^x to fire the gun. The said main spring by its engagement with the tripping lever E^s also causes the latter and the parts connected thereto to assume their normal 15 position.

What we claim and desire to secure by Letters Patent of the United States is:—

1. In firing mechanism for ordnance, the combination with the striker and the spring controlled cocking and firing lever connected thereto, of a rocking shaft, a tripping lever, means for connecting said shaft to the tripping lever, and a tripping piece pivotally mounted on said lever and engaging with the cocking and firing lever.

2. In firing mechanism for ordnance, the combination with the striker and its firing lever, of a rocking shaft, a tripping lever, an axis pin on which the firing lever is pivoted, means for rigidly connecting the said tripping lever to the axis pin, means for connecting said rocking shaft to the axis pin, and a tripping piece pivotally mounted on the said tripping lever and engaging with the firing lever.

3. In firing mechanism for ordnance, the combination with the striker and its firing lever, of a rocking shaft, a tripping lever, an axis pin on which the firing lever is pivoted, means for rigidly connecting the said tripping lever to the axis pin, means for connecting said rocking shaft to the axis pin, and a tripping piece pivotally mounted on the tripping lever and engaging with a 45 notch in the firing lever.

4. In firing mechanism for ordnance, the

combination with the striker and its firing lever, of a rocking shaft, a tripping lever, an axis pin on which the firing lever is pivoted, means for rigidly connecting the said tripping lever to the axis pin, means for connecting said rocking shaft to the axis pin, and a two armed tripping piece pivotally mounted on the tripping lever, one arm of which tripping piece engages with a notch in the firing lever.

5. In firing mechanism for ordnance, the combination with the striker and its firing lever, of a rocking shaft, a tripping lever, an axis pin on which the firing lever is pivoted, means for rigidly connecting the said tripping lever to the axis pin, means for connecting said rocking shaft to the axis pin, and a two armed tripping piece pivotally mounted on the tripping lever, one arm of which tripping piece engages with a notch in the firing lever and the other arm with a fixed surface.

6. In firing mechanism for ordnance, the combination with a striker and its firing lever, of a rocking shaft, a tripping lever, an axis pin on which the firing lever is pivoted, means for rigidly connecting the said tripping lever to the axis pin, a lever on one end of said shaft, a transversely arranged spindle, an intermediate firing lever on one end of said spindle, a guide member on the other end of the said spindle, a lever engaging with said guide member and connected to the axis pin carrying the tripping lever and the firing lever, and a two armed tripping piece pivotally mounted on the tripping lever, one arm of which tripping piece engages with a notch in the firing lever and the other arm with a fixed surface.

In testimony whereof we affix our signatures in presence of two witnesses.

ARTHUR TREVOR DAWSON.
GEORGE THOMAS BUCKHAM.
